UNITED STATES PATENT OFFICE.

ARTHUR V. DA COSTA, OF PROVIDENCE, RHODE ISLAND.

COMBINATION STEAM AND INTERNAL-COMBUSTION ENGINE.

Application filed March 23, 1921. Serial No. 454,743.

To all whom it may concern:

Be it known that I, ARTHUR V. DA COSTA, a citizen of the United States, residing at Providence, in the county of Providence and State of Rhode Island, have invented certain new and useful Improvements in Combination Steam and Internal-Combustion Engines, of which the following is a specification.

- 10 This invention relates to an improved construction of engine and an improved method of generating power in said engine; and the object of this invention is to provide an engine of this character having one or more internal combustion cylinders in which a charge of combustible fluid is compressed, fired and expanded to drive a piston, with which expanded charge another fluid of a lower temperature is mixed for the purpose of cooling the surrounding parts and of increasing the volume of the charge to act upon another driving element.

A further object of this invention is the provision of a steam generator located adjacent the engine cylinders, which generator is heated by burning an explosive charge in the cylinders and means being provided whereby steam is conducted from this generator to mix with the exploded charge after being expanded. By which construction it will be seen that the explosion in the engine cylinder performs two functions; first, it drives the piston and second, it generates heat to make steam in the generator. The next step in the operation is that the steam thus generated is admitted to the exploded and expanded charge, which performs three functions; first, the steam being at a lower temperature than the charge cools the cylinders and adjacent parts to the proper working temperature; second, the heat in the charge raises the temperature of the steam admitted to expand the same; and third, the admitting of steam into the charge increases the volume of the charge preparatory to acting upon another driving element.

The invention further consists in the provision of a pair of high-pressure, four-cycle internal combustion cylinders in which a charge is fired alternately when compressed and into which cylinders is admitted steam when the burnt charge has expanded, and a low pressure cylinder being located intermediate said high pressure cylinders

into which the charges from the high-pressure cylinders are alternately forced to impel each inward stroke of its piston.

This invention further consists in the provision of a turbine motor connected to the engine driving shaft and means being provided whereby the exhaust comprising the burnt expanded charge combined with the mixture of steam is conducted to this motor to drive the same.

With these and other objects in view, the invention consists of certain novel features of construction, as will be more fully described, and particularly pointed out in the appended claims.

In the accompanying drawings:—

Figure 1 is a sectional side elevation through the two high and intermediate low pressure cylinders, also showing the turbine motor mounted to cooperate with the rest of the engine in generating power.

Figure 2 is a rear view of the engine.

Figure 3 is a top view of the engine sectioned on line 3—3 of Figure 1 through the steam generator.

Figure 4 is an enlarged view showing a portion of the steam generator, also showing a detail of one form of automatic water supply control.

Figure 5 is an elevation showing the relative position of the thermal unit at the steam and water line for controlling the water supply to the generator.

Figure 6 is a diagrammatic view illustrating the general arrangement of the valve cam for controlling one of the high pressure cylinders whereby the valve is opened once each revolution of the cam shaft.

Figure 7 shows the low pressure cylinder and the arrangement of the cams on the cam-shaft whereby the exhaust valve is opened twice each revolution of the cam shaft.

Figure 8 is a diagrammatic section showing one form of water chamber for supplying the steam generator.

Figure 9 is a diagrammatic view illustrating the oil chamber as connected to the oil well and delivering oil therefrom to the crank splashing system.

Figure 10 is a detail of the cam shaft showing the arrangement of the intake and exhaust control cams.

It is well known in practice that the ordinary internal combustion engine even of the

four-cycle type, is very inefficient as it develops but a small percentage of the power in the fuel consumed, this inefficiency being due primarily to the great loss of heat both in radiation and in the escape of the hot products of combination. Special means such as a circulation of water or air about the cylinders being provided for carrying away this heat which in the old style internal combustion engine is both objectionable and troublesome. By my improved method I not only provide a simple and practical way of removing this heretofore wasted heat but I utilize the same to develop more power and by which method I practically double the efficiency of the engine, and the following is a detailed description of one means and method by which this result may be accomplished.

With reference to the drawings, 10 and 10^a designate a pair of high-pressure cylinders which are mounted upon a common case 11. In these cylinders are mounted pistons 12 and 12^a connected to their respective 25 cranks 13 by the rods 14, the cranks being connected to the shaft 15 mounted to run in bearings 16 in the casing 11.

Intermediate this pair of high pressure cylinders I have mounted a single low pressure cylinder 17 in which is mounted a piston 18 which is connected by means of the rod 19 to the crank 20 which latter is also connected to the crank shaft 15 and which has a throw greater than that of the high pressure cylinder cranks.

A single cylinder head 21 is shown as being connected to all of these cylinders, said head being constructed in the form of a thin chamber for carrying a comparatively small amount of water spread out in a thin layer to be generated quickly into steam by the heat of the explosions in the high pressure cylinders.

This head member in addition to serving as a steam generating chamber also serves as a valve head for carrying all of the intake and exhaust valves for all of said cylinders and these valves are all controlled from a common valve cam shaft 22 which is driven from the crank shaft 15 through gears 23 and 24 to run at one-half the speed of the crank shaft.

The intake valve 25 is opened from cam 26 through the lift 27 and rocker arm 28 to permit an explosive mixture to be drawn into the cylinder through the carburetor 29 and manifold 30 by the inwardly moving piston 13. On the next upward movement of this piston the valve 25 closes and the charge therein is compressed to a very high degree and when so compressed is fired through the action of the spark plug 55 in the usual way to now drive the piston in again to make its power stroke.

The exhaust valve to this cylinder is now

opened through the action of cam 32, lift 33, and rocker arm 34 about the time that the piston 12 has completed its power stroke. It will be observed that the valve 31 controls two passages, namely a small passage 36 70 leading to the interior of the generator 35, above the level of the water, and a main exhaust passage 37 leading to the cylinder 17. As the burning charge or exploded gases are forced outwardly by the piston 12, they divide, a portion passing through passage 36 into contact with the water in the generator 35, thereby quickly raising the temperature and pressure of the steam, and a portion passing into the cylinder 17. The discharge 80 of the burning gases into the generator 35 continues until the steam pressure builds up sufficiently to react and arrest movement of said gases toward the generator, whereupon, the steam will be forced out of the generator 85 and will unite with the gases in the passage 37. The mixed steam and gases enter cylinder 17 through said passage 37, driving the piston 18 inward. In due course the valve 31 is closed and the exhaust valve 38 of this 90 large cylinder is opened by action of the cam 39 through the lift 40 and rocker arm 41 to permit the escape of the exhaust from this cylinder through the pipe 42 to be conducted to another driving element hereinafter described.

During this action of piston 18, the other high pressure cylinder 10^a performs its function similar to that of cylinder 10 differing only by the relative periods of operation, that is, the inlet valve 43 is opened through the action of cam 44, valve lift 45 and rocker arm 46 to admit an explosive mixture through the branch 47 of the manifold by the intake stroke of the piston 12^a and after 100 its charge has been compressed it is fired by the spark plug 48, the piston under impact of this charge makes its power stroke after which its exhaust valve 49 is opened through action of the cam 50, lift rod 51 and rocker arm 52 to now admit steam from the chamber 35 through the port 53 into the expanded burnt charge, which mixture is then expelled by the rising piston 12^a through the channel 54 against the large piston which is now 105 raised again and is in position to receive it and be forced downward. By this construction it will be noted that while both of these high pressure pistons are down at the same time yet one is at the end of its intake stroke 110 while the other is at the end of its power stroke and vice versa. In other words the two high pressure cylinders are timed to exhaust alternately into the large cylinder to drive its piston downwardly at its each and every inward stroke after which the volume in this low pressure cylinder may be exhausted into the open air if desired to complete a full cycle of operations. In other 115 instances I may conduct this volume of com- 120

pound exhaust gases to act upon another driving element to generate more power and so more fully utilize the energy in the charge.

5 In the utilizing of this low pressure exhaust I preferably mount a turbine motor 56 in position to cooperate with the engine driving shaft to increase the power of the engine, the exhaust being conducted to this 10 turbine through the pipe 57. In practice I preferably provide a jack shaft 58 which is geared to the crank shaft 15 by the large gear 59 and pinion 60, to run at a much higher speed than the crank shaft and on 15 this jack shaft I preferably mount the turbine motor wheel 62. By this construction the turbine wheel serves a double purpose; first, it rotates at a very high velocity relative to the crank shaft and takes the place 20 of a fly-wheel; and second, the turbine wheel 62 is permitted to run at its required rate of speed to effect its maximum efficiency so that in addition to increasing the power 25 of the engine, the turbine upon being geared to run at a high velocity serves to steady the action of the engine to a greater extent than could a fly-wheel mounted directly upon the crank shaft.

After the compound gas has passed 30 through this turbine it is exhausted out through the pipe 61 and by its use practically all of the energy in the exhaust gases produced by the explosive mixture and the steam, has been utilized.

35 In constructing my improved steam generator the same may be made in any desired form to either inclose the cylinders if desired or place in any other desired position, but for convenience I have found that the 40 head member for the cylinders may be formed in a comparatively thin chamber whereby the heat from the exploded fuel under pressure is sufficient to act upon a thin film of water in this chamber to flash 45 the same quickly into steam.

In order to keep the water in this chamber at a constant predetermined level I have provided a pump 63 which comprises essentially a plunger 64 driven from the cam 50 shaft 22 through the knee lever 65 to draw the water from the tank 66 through pipe 75 and force the same upward through the supply pipe 67 into the chamber 35.

As it is found in practice desirable to provide some means for automatically controlling the height of the water in the chamber, I have mounted a thermally-controlled unit 55 therein, which comprises essentially a tube 68 mounted in the steam chamber, whose longitudinal axis is positioned approximately at the desired height of the water line in the chamber. In this tube I place a small quantity of specially prepared oil or other material 69 which is expanded and contracted by changes in high temperature 60

and in this cylinder I mount a piston 70 which is held back against the liquid by a compression spring 71 so that when the water 72 drops in the chamber to more completely expose the tube 68 to the steam, the 70 added heat of the steam expands the liquid therein forcing out the piston 70 to engage and raise the valve 73 from its seat admitting more water through the supply pipe 67 around through the inlet 74 to again raise 75 the level of the water about the tube and so cool and contract the liquid therein permitting the piston 70 under action of its spring to recede and seat its control valve 73. When this control valve is seated the pump 80 pressure generated in the space 76 serves to raise the relief valve 77 permitting the excess water pumped to return by way of the pipe 78 to the water reservoir 66, see Fig. 8.

I have shown and described one form of thermal element for automatically controlling the height of the water level in the generator, but any suitable means may be employed for this purpose.

As is well known the excessive or high degree of heat generated by exploding the charge under pressure is a detriment to the action of the usual internal combustion engine, and therefore, must be removed, which 95 has ordinarily been accomplished either in circulating cool water or air about the cylinders and in the removal of which heat as is well known, a large percentage of the energy in the fuel is thrown away. To ob- 100 viate this serious difficulty which has heretofore not been overcome in a practical way, I utilize this heat to generate steam and then I conduct a charge of this steam so generated into the expanded charge after 105 the piston has been forced down and the charge expanded, which steam being at a temperature lower than that of the charge in the cylinder, serves to at once take up this excessive heat and so cool off the cylinder 110 walls and surrounding parts, the volume of the steam admitted is itself at once expanded and upon mixing with the charge greatly increases the volume of the whole charge whose energy having been greatly increased by the 115 admission of steam thereto, is expelled by the rising piston, into the low pressure cylinder to drive down its piston and so do more work, and after the energy of the com- 120 pound charge has been thus further used and removed, it is again expelled and conducted to act upon the turbine engine 56 which is connected to cooperate with the pistons to do still more work and upon exhausting from the turbine both the heat and the pres- 125 sure of the compound charge has been practically all utilized in producing work.

Another advantage obtained by my improved method of admitting steam to the internal combustion cylinders is that the 130

4
steam serves to keep the cylinders entirely free of carbon thus removing a great source of trouble and maintaining a high degree of efficiency in the high pressure cylinders.
5 I have shown and described a pair of high pressure internal combustion cylinders which are arranged to exhaust their compound charge of steam and burnt gases alternately into a larger cylinder to do more work, but
10 I do not wish to be restricted to this particular arrangement of mechanism as the compound charge may be used to act upon any driving element to do more work; neither do I wish to be restricted to the admitting of steam necessarily into the cylinders for the purpose of cooling the same as any cooling medium which has been pre-heated by an explosive charge but which is of a temperature lower than that of the
15 charge in the cylinder, may be admitted thereto for the purpose of cooling the surrounding parts.

Having thus described one illustrative embodiment of my invention and the best mode known to me for carrying out my method,
25 I desire it to be understood that although specific terms are employed, they are used in a generic and descriptive sense and not for the purpose of limitation, the scope of the invention being defined and limited only
30 by the terms of the appended claims.

I claim:

1. A method of generating power comprising exploding a combustible charge within a cylinder to apply power to a movable element, separating a portion of the burning charge from the whole charge and utilizing the separated portion to produce high pressure steam, and causing said steam and the rest of said burning charge to react against a second movable element.
35

2. A method of generating power comprising exploding a combustible charge within a cylinder to apply power to a movable element, separating a portion of the burning charge from the whole charge and bringing it into direct contact with a body of steam to raise the pressure thereof, and causing said steam and the rest of said burning charge to react against a second movable element.
45

3. A method of generating power comprising exploding a combustible charge within a cylinder to apply power to a movable element, separating a portion of the burning charge from the whole charge and utilizing the separated portion to generate high pressure steam until said pressure reacts against the flow of the separated portion of said charge, and utilizing said reaction to cause said steam and the balance of said burning charge to actuate a second movable element.
55

4. A method of generating power comprising exploding a combustible charge
60

within a cylinder to apply power to a movable element, causing a portion of the burning charge less than the whole charge to flow into contact with a body of low pressure steam until sufficient pressure is generated to arrest said flow, and then utilizing said steam pressure and the balance of said burning gases to actuate a second movable element.
70

5. A method of generating power comprising exploding a combustible charge within a cylinder to apply power to a movable element, discharging the burning products in two streams, utilizing one stream to generate steam pressure, discharging the other stream into a second cylinder containing a movable element and simultaneously discharging steam pressure into the second cylinder.
75

6. A method of generating power comprising exploding a combustible charge within a cylinder to apply power to a movable element, discharging the burning products in two streams, utilizing one stream to generate steam pressure, discharging the other stream into a second cylinder containing a movable element, causing said steam to combine with the second steam of the burning discharge, and causing the combined steam and burning discharge to react against another movable element.
80

7. A method of generating power comprising exploding a combustible charge within a cylinder to apply power to a movable element, separating a portion of the burning charge from the whole charge and utilizing the separated portion to produce high pressure steam, causing said steam and the rest of said burning charge to react against a second movable element, and actuating a common shaft by means of the two movable elements.
100

8. A method of generating power comprising exploding a combustible charge within a cylinder to apply power to a movable element, separating a portion of the burning charge from the whole charge and utilizing the separated portion to produce high pressure steam, to a point where said pressure will react against the flow of said charge, and utilizing said reaction to cause said steam and the balance of said burning charge to actuate a second movable element, and causing both movable elements to actuate a common shaft.
110

9. In a compound motor, a steam generator, an internal combustion cylinder, means for firing a charge under pressure in said cylinder to actuate a movable element, means directing a portion of the exploded gases less than the whole charge into said generator to produce high pressure steam, means for combining the high pressure steam with the remainder of said gases, a second driving element, and means whereby said combination
125

charge may be caused to act upon said second driving element.

10. A motor comprising a steam generator, a high pressure internal combustion cylinder, a piston for compressing a charge in said cylinder, means for firing the compressed charge in said cylinder, means directing a portion of the exploded gases less than the whole charge into said generator to produce high pressure steam upon the firing of said charge, means for combining the steam thus generated with the remainder of said exploded gases, a cooperating low pressure cylinder, and means for discharging the 15 compressed compound charge into said low pressure cylinder.

11. A motor comprising a steam generator, a pair of cooperating high pressure cylinders, a charge compressing piston in each cylinder connected to a common drive shaft, means for firing explosive charges in said cylinders alternately to drive said shaft, means directing a portion of the burning charge in each cylinder less than the whole 25 charge into said generator to produce high pressure steam, means for combining the steam thus generated with the remaining portions of the product of combustion in said cylinders, a cooperating low pressure 30 cylinder, and means for forcing the compound charges alternately from said high pressure cylinders into said low pressure cylinder.

12. A motor comprising a drive-shaft, a high pressure internal combustion cylinder, a piston in said cylinder connected to said shaft, a steam generator arranged to be heated by radiation from cylinder, means for directing a portion of the exploded gases 40 in said cylinder less than the whole charge into said generator to produce high pressure steam, a cooperating low pressure cylinder, and valve mechanism for controlling the flow of the increased volume of said combined charge to said low pressure cylinder as it is expelled thereinto from said high pressure cylinder.

13. A motor comprising a pair of internal combustion cylinders, a piston in each cylinder, a common drive-shaft actuated by said pistons, a steam generator in proximity to said cylinders, means for introducing water to said generator, means for firing the charges in said cylinders alternately when compressed, means directing portions of the exploded gases in said cylinders, less than the whole charge into said generator to produce high pressure steam, means combining steam pressure with the remainder of the 55 exploded gases, a third cooperating cylinder also connected to said shaft, and means for conducting said combined charges from said high-pressure cylinders alternately to said

third cylinder to cooperate with the other cylinders to do more work.

14. A motor comprising a pair of internal combustion cylinders, a charge-compressing piston in each cylinder, a common drive shaft actuated by said pistons, a steam generator, means directing portions of the exploded gases in said cylinders, less than the whole charge into said generator to produce high pressure steam, means for firing the charge for driving the pistons and heating said generator, means for combining the 70 high pressure steam from said generator with the remainder of said exploded gases, a third cylinder provided with a piston also connected with said shaft, means for conducting the combined charges from said high pressure cylinders alternately to said third cylinder, and means for introducing water to said generator.

15. A motor comprising a pair of internal combustion cylinders, a low pressure cylinder located intermediate said pair of cylinders, a piston in each of said cylinders, a common crank shaft connected with all of said pistons, means whereby the charges in said pair of cylinders is compressed and 90 fired at every alternate stroke, a steam generator in proximity to said cylinders, means directing portions of the exploded gases in said cylinders less than the whole charges into said generator to produce high pressure 95 steam, valves for permitting a flow of steam from said generator to said high pressure cylinders in combination with the rest of the exploded gases, and means whereby the rising pistons force these compound charges 100 alternately from said pair of cylinders into said low pressure cylinder to impel its every inward stroke.

16. A motor comprising a pair of internal combustion cylinders, charge-compressing pistons in said cylinders, a common drive-shaft actuated by said pistons, a steam generator in the cylinder heads, means for firing the charge when compressed in said cylinders, means directing a portion of the exploded gases less than the whole charge in each cylinder into said generator to produce high pressure steam, a third cooperating cylinder having a piston also connected to said shaft, valve-controlled mechanism for admitting steam from said generator into said third cylinders, means for conducting the remaining portions of the exploded gases into said third cylinder in combination with the steam while it is flowing into said cylinder, means for introducing water to said generator, and means for controlling the height of the water therein.

In testimony whereof I affix my signature.

ARTHUR V. DA COSTA.
